DESIGN FOR A CHAIR OR SIMILAR ARTICLE

Harry J. Terker, Brooklyn, N. Y., assignor to
Greenpoint Metalcraft Incorporated, Brook-
lyn, N. Y.

Application April 29, 1936, Serial No. 62,360

Term of patent 7 years

To all whom it may concern:

Be it known that I, Harry J. Terker, a citizen of the United States and residing at Brooklyn, in the county of Kings and State of New York, have invented a new, original, and ornamental Design for a Chair or Similar Article, of which the following is a specification, reference being had to the accompanying drawing, forming part thereof, and in which

The figure shows a perspective view of a chair having two front members, which are curved backwardly to form side arms for the chair. Ex-

tending rearwardly from an intermediate portion of these front members are two rear members which curve downwardly toward the floor.

As shown, the members are fluted or beaded, and are connected by transverse pieces, one being shown connecting the two rear members and the other connecting the rear ends of the front members.

What is claimed is:

The ornamental design for a chair or similar article substantially as shown and described.

HARRY J. TERKER.
